US00D900675S

(12) **United States Design Patent** (10) Patent No.: **US D900,675 S**
(45) Date of Patent: **** Nov. 3, 2020**

(54) **INTELLIGENT DEVICE**

(71) Applicant: **PowerVision Tech (SuZhou) Ltd.**,
Changshu, Jiangsu Province (CN)

(72) Inventors: **Junjie Jia**, Changshu (CN); **Liye Chen**,
Changshu (CN)

(73) Assignee: **PowerVision Tech (SuZhou) Ltd.**,
Changshu, Jiangsu Province (CN)

(**) Term: **15 Years**

(21) Appl. No.: **29/707,762**

(22) Filed: **Oct. 1, 2019**

(30) **Foreign Application Priority Data**

Apr. 1, 2019	(CN)	2019 1 0257812
May 20, 2019	(CN)	2019 1 0426335

(57) **CLAIM**

The ornamental design for an intelligent device, as shown and described.

DESCRIPTION

FIG. 1 is a front view of an intelligent device showing my new design;

FIG. 2 is a rear view of an intelligent device showing my new design;

FIG. 3 is a left view of an intelligent device showing my new design;

FIG. 4 is a right view of an intelligent device showing my new design;

FIG. 5 is a top view of an intelligent device showing my new design;

FIG. 6 is a bottom view of an intelligent device showing my new design; and,

FIG. 7 is a perspective view of an intelligent device showing my new design.

The portions of the intelligent device shown in broken lines form no part of the claimed design.

1 Claim, 6 Drawing Sheets
